UNITED STATES PATENT OFFICE.

LEWIS R. BROWN, OF SOUTH ORANGE, NEW JERSEY, AND FRED H. WENTWORTH, OF NEW YORK, N. Y.; SAID WENTWORTH ASSIGNOR OF THIRTY ONE-HUNDREDTHS TO SAID BROWN.

ELECTRIC SWITCH.

No. 818,226.

Specification of Letters Patent.

Patented April 17, 1906.

Application filed May 5, 1905. Serial No. 253,943.

To all whom it may concern:

Be it known that we, LEWIS R. BROWN, a resident of South Orange, in the county of Essex and State of New Jersey, and FRED H. WENTWORTH, a resident of the city of New York, borough of Manhattan, in the county and State of New York, citizens of the United States, have invented a new and Improved Electric Switch, of which the following is a full, clear, and exact description.

Our invention relates to a switch to be operated by an electric current and to be controlled in any desired manner—as, for example, by a time-clock—for the purpose of making and breaking any desired kind of an electric circuit.

The principal objects of our invention are to provide means for effectively making and breaking contact and leaving the various electrical connections of the device in such condition when not in use that no current will flow through them; further, to provide means which can be operated by the time-clock or similar device for operating both the making and breaking parts of the device and for providing a switch which can be used in any desired kind of electric circuit and for operating any desired kind of an electrical instrument.

Further objects of the invention will appear in the course of the subjoined description.

Reference is to be had to the accompanying drawings, forming a part of this specification, in which similar characters of reference indicate corresponding parts in all the figures.

Figure 1 is a diagrammatic view showing a system of connections which can be used with our invention. Fig. 2 is an elevation showing the inside of a receptacle and a preferred form of our invention therein, and Fig. 3 is a sectional view of certain details to be described.

Referring first to Fig. 1, the general plan of the electrical connections illustrated will be described. A three-wire system 10 is connected in any ordinary manner with an electric light 11 or with any other desired kind of an electrical instrument which it may be desired to connect with and disconnect from the three-wire system. It will be understood that the switch can be applied to any kind of

an electric circuit and that the three-wire system is illustrated for convenience. The light 11 is shown as connected with a neutral wire by means of a wire 12 and by a connection 13 with a mercury-cup 14. This mercury-cup is also connected by a wire 15 with an electromagnet 16, which has a connection 17 to a contact-piece 18. A lever 19 is pivoted upon an element 20, constituting a part of a frame which will be referred to later, the frame being connected by a wire 21 with the wire 12. This lever is adapted to engage with the contact-piece 18. Upon the same frame is pivoted another lever 22, which is adapted to engage with a contact-piece 23, connected by a wire 24 with a second electromagnet 25. This electromagnet is connected at the opposite side by a wire 26, through a binding-post 27, with a rod 28, which is secured to its own armature 29. This rod 28 normally supports a contact-making element 30, which constitutes the armature of the magnet 16 and which is provided with a bar 31, adapted to enter the mercury-cup 14. Secured to the element 30 is a rod 32, bent upwardly and provided with a projection 33, entering a stationary mercury-cup 34, which by means of a wire 35 is shown as connected with the positive wire of the three-wire system. It will be seen that in order to conduct a current constantly through the light 11 the rod 31 must be in the mercury-cup 14. The current is then conducted from the positive through the elements 35, 34, 33, 32, 31, 14, 13, 11, and 12 back to the neutral wire of the main circuit. In order to provide the necessary motions to control the turning of the current onto and off from this circuit, the two levers 19 and 22 are manipulated in any desired manner. This manipulation can occur by hand, by switches, by electrical connections from distant points, by a time-clock system, and the like. We have illustrated a time-clock system having a shaft 36, which is controlled by any desired mechanism, so as to rotate regularly. The shaft is provided with a dial 37, indicating the hours and minutes, if desired. Upon the shaft, and preferably above the dial, are located two disks 38 and 39, of insulating material. These two disks are capable of being turned about the shaft 36 and fixed in any desired position. They are provided with notches 40 and 41,

respectively, for receiving projections 42 and 43 upon the levers 22 and 19. These notches are provided with sharp shoulders on one side and with inclined surfaces on the other, so that as the disks rotate with the shaft 36 after being secured in any desired position the circumferences of the disks will normally hold the two projections 42 and 43 in the position shown, so that the levers 19 and 22 will remain out of contact with the contact-pieces 18 and 23; but when the clock-shaft rotates sufficiently to bring the notches opposite the projections on the bars the latter will be allowed to move on account of any desired motive power—as, for example, weights 44—upon the outer ends of the two levers. This will permit the levers to make contact with the contact-pieces 18 and 23. The effect of this will now be described.

Supposing the shaft 36 to be rotated slightly in the direction of the arrow, the projection 42 will enter the notch 40 on account of the action of the weight 44, and the end of the lever will engage the contact-piece 23. This completes a circuit through the elements 35, 34, 32, 30, 28, 26, 25, 24, 23, 22, and 21 back to the wire 12 and the neutral wire of the system, and consequently a current will flow through these connections and energize the magnet 25, so as to retract the armature thereof and remove the bar 28 from the bottom of the armature 30. This will permit the armature to drop, taking with it the bar 31 and the connection 32. The bar 31 will enter the mercury-cup 14, and a new circuit will be set up from the positive of the main circuit through the elements 35, 34, 32, 31, 14, 13, 11, and 12 to the neutral, which will light the lamp. Upon further rotation of the shaft 36 the rear slanting surface of the notch 40 will force the projection 42 out to the circumference of the disk 38 and break the contact at the other end of the lever 22, so that no more current will flow through the circuit connected therewith. This relieves the electromagnet 25 of all tension except from that of a spring 45 therein. (Shown in Fig. 2.) This spring, therefore, will be permitted to force the armature outwardly again until the part 28 engages the armature 30; but by this time this armature is in its lowermost position, and consequently the rod 28 will engage with an insulation 46 upon the armature, and no current will be conducted through it even if the contact at the contact-piece 23 is made. The parts will remain in this position, no current passing through any part of the line except that necessary for supplying the lamp 11, until the disk 39 has rotated enough to bring the notch 41 opposite the projection 43. Then contact will be made between the lever 19 and the contact-piece 18 in the same manner as that described above. This will permit a current to flow from the mercury-cup 14, through the wire 15, magnet 16, and

wire 17, to the contact-piece 18, lever 19, and frame 20. This current is then conducted by the wire 21 back to the wire 12, and therefore forms a shunt from the circuit feeding the lamp. This energizes the magnet 16 and draws the armature 30 up into the position shown in Fig. 1 and breaks the circuit to the lamp. The spring acting on the armature 29 forces the bar 28 into position to hold the armature 30 in elevated position, and as soon as the disk 39 has rotated a slight distance farther the contact with the lever 19 is broken, and the parts are restored to the original position with the lamp unlighted. It will be observed that all these operations are accomplished without wasting current through any live wires except during or immediately after a change is made in the light or other electrical instrument 11. It will further be seen that all parts are capable of operating with great rapidity and efficiency and that no serious complications of construction are necessary in making the device.

Referring now to Figs. 2 and 3, a more complete description of certain parts of the apparatus will be given. Fig. 2 shows a receptacle 47, having a cover 48, adapted to be secured thereto by means of thumb-bolts 49. The parts 14, 16, 25, 34, and 20 (the latter being the frame of the clock) are mounted upon an insulating-plate 50 at the back of the receptacle, and most of the electrical connections are made by means of wires insulated from each other and located behind the insulating-plate. The mercury-cups 14 and 34 are preferably provided with slots 51, by which they can be adjustably held in position by screws 52, which may also act as binding-screws. The magnet 25 is provided with an internal shell 53, having a shoulder 54 for engaging the spring 45 to normally hold it in position to force the armature outwardly. The rod 31 is preferably screwed into the armature 30 and the insulation 46 secured upon the outside of it next to the armature. The bottom of the armature forms a shoulder for receiving the bar 28. The conductor 32 is preferably connected to the bottom or some other convenient portion of the armature. A fuse 56 is represented in the conductor 24.

The several parts of the time-clock need not be described; but the drawings show a pointer 57, which can be employed in setting the dial 37 and for registering the time on the dial. The disks 38 and 39 are provided with marks 58, adapted to register with the pointer when the projections on the levers are in the notches 40 and 41.

Having thus described our invention, we claim as new and desire to secure by Letters Patent—

1. An electric switch comprising a contact-making element, means for supporting said element in inoperative position, an electric circuit

cutting means connected with the electric circuit for releasing said element to cause it to complete another electric circuit, and means on said element for opening said first-mentioned electric circuit when it has released the element.

2. The combination with a main circuit, of an electric switch comprising a contact-making bar, a contact device, means for normally holding said bar in elevated position out of contact with said contact-making device, means for releasing said bar and permitting it to drop into contact with said device, electrical connections from said bar to one member of the main circuit, and electrical connections from said means to another member of the main circuit, said means being in electrical connection with the bar when holding it in elevated position and insulated therefrom when the bar is in contact with the contact-making device.

3. The combination with a main circuit, of an electric switch comprising a contact-making bar, a contact device, means for normally holding said bar in elevated position out of contact with said contact-making device, means for releasing said bar and permitting it to drop into contact with said device, electrical connections from said bar to one member of the main circuit, and electrical connections from said means to the other member of the main circuit, said means being in electrical connection with the bar when holding it in elevated position, said contact-making bar being provided with insulation for preventing electric connection between it and the means for releasing it when the bar is released.

4. The combination with a main circuit, of an electric switch comprising a vertically-movable bar, a mercury-cup located below the bar, a bar for holding the first-mentioned bar in elevated position, means for retracting said second bar and permitting the first-mentioned bar to drop into the mercury-cup, electrical connections from the first-mentioned bar to one member of the main circuit, and electrical connections from the mercury-cup to the other member of the main circuit.

5. The combination with a main circuit, of an electric switch comprising a vertically-movable bar, a mercury-cup located below the bar, a bar for holding the first-mentioned bar in elevated position, means for retracting said second bar and permitting the first-mentioned bar to drop into the mercury-cup, electrical connections from the first-mentioned bar to one member of the main circuit, electrical connections from the mercury-cup to the other member of the main circuit, said first-named bar being provided with insulation for preventing the passage of a current between it and the second bar when the first bar is in the mercury-cup, and means

for returning the first-mentioned bar to elevated position.

6. The combination with a main circuit, of an electric switch comprising a contact-making bar, a contact device, means for normally holding said bar in elevated position out of contact with said contact-making device, means for releasing said bar and permitting it to drop into contact with said device, electrical connections from said bar to one member of the main circuit, electrical connections from said means to the other member of the main circuit, said means being in electrical connection with the bar when holding it in elevated position, and means for returning said bar to elevated position, said means comprising an electromagnet.

7. The combination with a main circuit, of a mercury-cup connected therewith, an electrical instrument between the mercury-cup and the main circuit, a vertically-movable bar adapted to enter the mercury-cup, an electromagnet, a bar connected with said electromagnet and adapted to hold said first-named bar in elevated position out of the mercury-cup, and means for connecting the electromagnet with the main circuit to energize it and withdraw the second bar from contact with the first bar.

8. The combination with a main circuit, of an electrical instrument connected therewith, a mercury-cup connected with the electrical instrument, a movable bar adapted to enter the mercury-cup and permanently connected with the main circuit, an electromagnet, a bar connected with the electromagnet and controlled thereby, said bar being adapted to hold the first-named bar in elevated position out of the mercury-cup, and electrical connections between the said last-named bar, said electromagnet and the main circuit, for exciting the electromagnet and withdrawing the bar from its supporting position.

9. The combination of a mercury-cup, a movable bar adapted to enter the mercury-cup, an electromagnet, a bar connected to the electromagnet and controlled thereby, said bar being adapted to hold said first-named bar out of the mercury-cup, and electrical connections between the last-named bar and the electromagnet for exciting the latter and withdrawing the bar from its supporting position.

10. The combination of an electrical circuit, a mercury-cup, a vertically-movable bar adapted to enter the cup connected with said circuit, an electromagnet, a bar connected with said electromagnet and adapted to engage the said first-named bar and hold it in elevated position out of the mercury-cup, and means for energizing the electromagnet to withdraw the second-named bar from contact with the first bar.

11. In an electric switch, the combination of a contact-making bar, a contact device,

means for normally holding said bar out of contact with said device, means for releasing the bar and permitting it to move into contact with said device, said means being an electrical connection with the bar when holding it out of contact, and means for returning said bar to a position out of contact with said device.

12. In an electric switch, the combination of a vertically-movable bar, a mercury-cup located below the bar, a second bar for holding the first-mentioned bar in an elevated position, means for retracting the second bar and permitting the first-named bar to drop into the mercury-cup, said first-named bar being provided with an insulation for preventing the passage of the current between it and the second bar when the first bar is in the mercury-cup, and means for returning the first-mentioned bar to elevated position.

13. In an electric switch, the combination of a vertically-movable conducting-bar connected with a source of power, a mercury-cup located below the bar, a second bar for holding the first-mentioned bar in elevated position, and means for retracting the second bar and permitting the first-mentioned bar to drop into the mercury-cup.

14. In an electric switch, the combination of a contact-making bar, a contact device, means for normally holding said bar in ele-

vated position out of contact with said contact device, and means for releasing said bar and permitting it to drop into contact with said device, said means being in electrical connection with the bar when holding it in elevated position, and said contact-making bar being provided with insulation for preventing electric connection between it and the means for releasing it when the bar is raised.

15. The combination with a main circuit, of an electrical instrument connected therewith, a contact device electrically connected with the electrical instrument, a movable bar adapted to engage said contact device and electrically connected with the main circuit, whereby when the bar engages the contact device a circuit will be completed through the electrical instrument and bar, an electromagnet for supporting said bar, a circuit connected with the electromagnet, means for making and breaking said circuit, an electromagnet for moving said bar to position out of contact with the contact-making device, and means for controlling the admission of a current to the last-named electromagnet.
